UNITED STATES PATENT OFFICE.

MAX ROCKSTROH, OF KLEIN-SEDLITZ, GERMANY.

BED-PLATE FOR PRINTING MACHINERY.

No. 874,626.

Specification of Letters Patent.

Patented Dec. 24, 1907.

Application filed August 1, 1906. Serial No. 328,746.

To all whom it may concern:

Be it known that I, MAX ROCKSTROH, director, a subject of the German Emperor, residing at Klein-Sedlitz, Germany, have invented certain new and useful Improvements 5 in Bed-Plates for Printing Machinery, of which the following is a specification.

The requirements of printing, which are constantly growing more stringent, render it 10 indispensable in printing machinery that vibrations should be reduced to the greatest possible extent.

The bedplate of printing presses has heretofore been composed of a large number of 15 separate parts; usually it has consisted of a number of blocks upon which the rails were screwed down and of laterally arranged parts mounted upon the bedplate for the reception of the cylinder bearings. When very large 20 sheets such as are now frequently employed in book printing are used, and the press runs at a very high speed, it often happens that through the inertia of the masses, especially 25 that of the reciprocating carriage, there are set up in the press vibrations which when delicate pictures are to be printed, affect the work injuriously, by causing the parts to become loose and to shift their positions and the fine screws of the autotypes to be worn 30 out prematurely, when larger editions are printed.

To render the press stable it is consequently necessary that the bedplate should consist of as few separate parts as possible 35 and that the screwing together of separate pieces should be reduced to a minimum. For this purpose in a press in accordance with this invention, the bedplate together with the guides for the driving mechanism 40 and the supports for the press stone and the printing cylinder, are formed in two parts only. The two halves of the bedplate together with the guides and with the cylinder bearings form the entire supporting frame- 45 work. The two halves are screwed together and, by means of the spring wedges, rigidly connected with each other. As the pressure exerted can act only in a vertical direction from the printing cylinder bearings to the

guides, it is impossible that the bedplate 50 should ever change its position.

Figure 1 of the accompanying drawing is a side elevation of a two-part bedplate in accordance with this invention. Fig. 2 is an end elevation of the same viewed in the direction of the arrow in Fig. 1; and Fig. 3 is a plan thereof.

The bedplate with the guides and the cylinder bearings consists, as shown in Figs. 2 and 3, of the two halves *a* which together 60 with the bearing *b* of the cylinder and the guides *c* belonging thereto constitute the entire bedplate. The end of the driving mechanism of the carriage slides on the surfaces *d*. The spring wedges *e* by means of which the 65 two halves of the bedplate are rigidly secured together are shown in Figs. 1 and 2.

Having now particularly described and ascertained the nature of my said invention and in what manner the same is to be performed, I declare that what I claim is:

1. In a printing press, a frame composed of two side sections having standards forming bearings for a cylinder, said sections also forming a bed plate, guide ribs arranged longitudinally of the bed plate, said sections provided with grooves forming carriage slide, means for connecting the sections, and wedge members for securely holding the sections together. 80

2. In a printing press involving a frame, two sections forming a ribbed bed plate, each of said sections having standards forming bearings for a printing press cylinder, said sections having guide-ways forming carriage 85 slides, each of said sections being formed in a single piece, means for joining the sections to each other, and wedges interposed between the sections to rigidly hold the latter in proper position with respect to each other. 90

In testimony whereof I have hereunto set my hand in presence of two subscribing witnesses.

MAX ROCKSTROH.
